(57) **CLAIM**

The ornamental design for the “patch panel for communication equipment,” as shown.

DESCRIPTION

FIG. 1 is a front perspective view of a first embodiment of the patch panel for communication equipment showing our new design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken line showing of the environment is for illustrative purpose only and forms no part of the claimed design.
